UNITED STATES PATENT OFFICE.

JOSEPH M. EMERICK, OF SALEM, OREGON.

MEANS FOR SHAPING THE RAKER-TEETH OF SAWS.

1,271,295.

Specification of Letters Patent.

Patented July 2, 1918.

Application filed March 15, 1917. Serial No. 155,042.

To all whom it may concern:

Be it known that I, JOSEPH M. EMERICK, a citizen of the United States, residing at Salem, in the county of Marion and State of 5 Oregon, have invented a new and useful Means for Shaping the Raker-Teeth of Saws, of which the following is a specification.

The present invention appertains to saw 10 sets, and aims to provide a novel and improved device of that character adapted especially for use with cross cut saws.

It is the object of the invention to provide an implement of the nature indicated 15 having novel means for engaging and accommodating the saw, having novel means for shaping the raker teeth, having novel means for holding a file to file the points of the teeth, and having other improved 20 features to enhance the utility and efficiency thereof.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 25 within the scope of what is claimed, without departing from the spirit of the invention.

The invention is illustrated in the accompanying drawings, wherein:—

35 Figure 1 is a plain view of the improved device.

Fig. 2 is a rear view thereof.

Fig. 3 is a front view, showing a portion of the saw in dotted lines.

40 Fig. 4 is a vertical section taken on the line 4—4 of Fig. 2.

In carrying out the invention, there is provided an elongated body 1 which will be referred to as disposed longitudinally of 45 the implement, said body being preferably cast from suitable metal and having a base plate 2 at one end to fit either side of the saw. The plate has the laterally projecting wings 3 projecting toward opposite 50 sides, and similarly projecting secondary wings 4 between the ends of the body, while the wings 3 are located near the lower end of the body. The body 1 is provided at its other end with an outstanding boss 5 having 55 a longitudinal axis arranged approximately

in the plane of the plate 2 and the boss or member 5 being spaced from the plate 2, and being provided with extensions 6 projecting laterally toward opposite sides in the same direction as the wings 3 and in a plane at 60 right angles to the plane of the plate 2. Two bars or elongated plates 7 have their adjacent ends overlapping and secured to the extensions 6 by means of screws 8 or otherwise, and the bars 7 project away from 65 one another in the same direction as the extensions 6 and are substantially in the same plane as said extensions. The bars or plates 7 are provided with hard surfaces 9 to contact with the points of the saw teeth, said 70 bars 7 being arranged to extend along the toothed edge of the saw blade with the plate 2 resting against or adjacent to one side of the plate.

In order to hold the device in place when 75 applied to the saw, and to facilitate the application of the device thereto, there is provided a pair of saw engaging members 10 extending longitudinally across the rear surfaces of the wings 3 and provided with 80 longitudinal slots 11 open at one end and receiving bolts 12 extending rearwardly from the wings 3, wing nuts 13 being threaded upon the bolts to clamp the members 10 against the wings. The members 10 85 are provided at the closed ends of the slots 11 with hooks 14 projecting forwardly to engage the ends of the recesses of the toothed edge of the saw between a raker tooth 15 and the cutting teeth 16, as seen in Fig. 3. 90 When the nuts 13 are loosened, the members 10 can be adjusted longitudinally of themselves and angularly around the bolts 12 as pivots, in order that the hooks 14 can be positioned properly. When the plate 2 95 is placed against one side of the saw blade, the hooks 14 can be projected through the respective recesses at opposite sides of the raker tooth 15, to properly position the device with respect to said raker tooth. 100

As a means for clamping a file or abrasive member against the bars 7, for filing the points of the saw teeth, the wings 4 are provided with rearwardly projecting lugs 17 through which clamping screws 18 are 105 threaded. Thus, when a file or elongated abrasive member 19 is placed against the faces of the bars 7 adjacent to their rear edges, the screws 18 can be screwed toward the file to clamp it against said bars, as seen 110

in Fig. 2. Then, when the members 10 are removed or reversed, so that their hooks 14 will not interfere with the movement of the device, the device can be reciprocated along 5 the saw with the bars 7 sliding along the points of the teeth and with the plate 2 sliding along one side of the blade. The file 19 is thereby carried along the points of the teeth for filing the points thereof, and the 10 device can be applied to both sides of the saw, as will be apparent.

The boss 5 is provided with a longitudinal bore 20 extending therethrough, provided with a counter bore or recess 21, the bore 20 15 being in approximately the same plane as the plate 2, and a plunger 22 is slideable loosely through the bore 20. The plunger 22 has a head 23 upon its outer end adapted to be struck by a hammer or other suitable 20 implement. An adjustable nut 24 is threaded upon the plunger 22 between the head 23 and boss 5, and a coiled wire expansion spring 25 surrounds the plunger and is confined between the nut 24 and the bottom of 25 the counter bore 21 whereby to move the plunger 22 outwardly or upwardly by spring tension. The spring 25 is seated in the counter bore 21, and the nut 24 can be adjusted to regulate the tension of the 30 spring. Engaged upon the inner end of the plunger 22 is a swage 26 slideable along the body or frame 1 between the boss 5 and the plate 2. The swage 26 is secured to the plunger 22 by means of a set screw 27 or 35 otherwise, and is provided with beveled portions 28 to engage the points of the raker tooth 15 and bend them apart and bring them into proper position. Thus, when the 40 device is applied to the saw, as indicated in Fig. 3, the head 23 being struck with a hammer, will force the swage 26 against the tooth 15 between the points thereof, and the beveled portions 28 will set the points of 45 said teeth, the blade being retracted from the tooth by the spring 25.

The device is also provided with means for bending the teeth toward opposite sides to set them, and for this purpose, the body or frame member 1 is provided at that end 50 which has the boss 5, with an outstanding anvil 29 opposite to the boss. The anvil 29 has a surface 30 against which the saw blade or tooth is adapted to rest, and beyond the surface 30, the anvil has an inclined 55 surface 31 sloping from the surface 30, as

seen in Fig. 4. Above the surface 31 is mounted a swage member or head 32 having lugs 33 pivoted to lugs 34 upstanding from the anvil 29. A spring 35 tends to raise or move the member 32 away from the surface 31, and the member 32 is provided with a beveled portion 36 to move adjacent to and parallel with the surface 31 when the member 32 is struck by a hammer or other suitable implement. By placing the saw upon 60 the anvil with the pointed end of the tooth overhanging the surface 31, the member 32 can be struck by a hammer, and will bend the point of the tooth against the surface 31. The saw can be reversed to bend the 70 teeth toward opposite sides as will be obvious.

Having thus described the invention, what is claimed as new is:—

1. A device of the character described, 75 embodying a body having a plate, clamping elements carried by said plate, slotted holding members adjustably engaging said elements and having portions to engage a saw at opposite sides of a raker tooth, and a 80 swage movably carried by the body and engageable with the end of said tooth.

2. A device of the character described, having a plate to bear against one side of a saw and a member in a plane at right angles to said plate to contact with the points of the saw teeth, means engageable with the 85 saw for positioning said plate relative thereto, and a swage movable against the end of one tooth.

3. A device of the character described, 90 embodying a body having a plate to bear against one side of a saw and members projecting in opposite directions and in a plane at right angles with said plate to bear against the points of the saw teeth, a swage carried by the body between said members to engage the end of a raker tooth, and adjustable means carried by the body engageable with the saw at opposite sides of said 100 tooth to hold the body in place relative to said tooth.

In testimony that I claim the foregoing as my own, I have hereto affixed my signature in the presence of two witnesses.

JOSEPH M. EMERICK.
